(57) **ABSTRACT**

Embodiments are directed to structural fuses and connection systems including the same. An example structural fuse includes a plurality of cutouts formed in the plate. The cutouts are configured to cause at least one first yield region of the plate to yield when a first load is applied to the plate. Optionally, the plurality of cutouts are configured to cause at least one second yield region to yield when a second load is applied to the plate. At least a portion of the first yield region is distinct from at least a portion of the second yield region and the first load is different than the second load.

STRUCTURAL FUSES AND CONNECTION SYSTEMS INCLUDING THE SAME

CROSS-REFERENCE TO RELATED APPLICATION

This application claims priority to U.S. Provisional Patent Application No. 63/174,706 filed on Apr. 14, 2021, the disclosure of which is incorporated herein, in its entirety, by this reference.

BACKGROUND

In buildings and other large structures, various components (e.g., beams, columns, braces, and/or walls) are connected to each other. The parts of the building and the connections between them are designed so they will not fail catastrophically under the expected loads. The load effects that are transmitted from one part to another include: axial forces, shear forces, and bending moments.

When designing structures to resist severe earthquakes or wind loads, engineers may rely on ductility to prevent catastrophic failure. Engineers may design certain parts of the building to yield in a controlled manner in order to accommodate the large movements associated with severe earthquake or wind loads. The parts of the structure that are typically designed to yield in a controlled manner are beams, braces, walls, and/or columns.

In order to control yielding, engineers may designate a yielding component (such as a brace or beam) and then design all the associate components to be stronger. This approach is called “capacity based” design. Sometimes a yielding component is oversized due to certain requirements, and then “capacity based” design has a cascading effect, resulting in oversizing all associate components. This may lead to structures that are expensive to construct.

After a severe earthquake or wind, the parts of the structure that have been yielded may require repair. Past experience has demonstrated that it is difficult to remove and replace structural components like beams, braces, walls, and columns. In many cases, it is impractical to repair the buildings. Thus, current design methods result in buildings that are safe for severe earthquakes and wind (i.e., the buildings will not collapse), but are not resilient (i.e., the buildings may have to be demolished because they are difficult to repair).

Some design procedures determine structural capacity based on the loads that can be carried when a “collapse mechanism” forms. This is known as “plastic design.” Plastic design procedures are only valid when the structural components have certain cross-sectional characteristics that will enable them to yield without experiencing instability. Some structures, particularly those known as “metal buildings” have member cross-sectional characteristics that disqualify them for plastic design.

SUMMARY

Embodiments are directed to structural fuses and connection systems including the same. In an embodiment, a structural fuse is disclosed. The structural fuse includes at least one plate and at least one first cutout formed in the at least one plate. The at least one first cutout is configured to form at least one first yield region. The at least one first yield region is configured to preferentially yield when a first load is applied to the plate. The structural fuse also includes at least one second cutout formed in the at least one plate. The at

least one second cutout is configured to form at least one second yield region. The at least one second yield region is configured to preferentially yield when a second load is applied to the plate. At least a portion of the at least one first yield region is distinct from at least a portion of the at least one second yield region. The first load is different than the second load.

In an embodiment, a frame is disclosed. The frame includes a first component, a second component, and a connection system attaching the first component to the second component. The connection system includes at least one structural fuse. The at least one structural fuse includes at least one plate and at least one first cutout formed in the at least one plate. The at least one first cutout is configured to form at least one first yield region. The at least one first yield region is configured to preferentially yield when a first load is applied to the plate. The at least one structural fuse also includes at least one second cutout formed in the at least one plate. The at least one second cutout is configured to form at least one second yield region. The at least one second yield region is configured to preferentially yield when a second load is applied to the plate. At least a portion of the at least one first yield region is distinct from at least a portion of the at least one second yield region. The first load is different than the second load. The first component and the second component are independently selected from a beam, a column, or a wall plate.

In an embodiment, a frame is disclosed. The frame includes a first component, a second component, and a connection system attaching the first component to the second component. The connection system includes at least one structural fuse. The at least one structural fuse includes at least one plate and at least one first cutout formed in the at least one plate. The at least one first cutout is configured to form at least one first yield region. The at least one first yield region is configured to preferentially yield when a first load is applied to the plate. The first component is a beam and the second component is a beam or a wall plate.

Features from any of the disclosed embodiments may be used in combination with one another, without limitation. In addition, other features and advantages of the present disclosure will become apparent to those of ordinary skill in the art through consideration of the following detailed description and the accompanying drawings.

BRIEF DESCRIPTION OF THE DRAWINGS

The drawings illustrate several embodiments of the present disclosure, wherein identical reference numerals refer to identical or similar elements or features in different views or embodiments shown in the drawings.

FIG. 1A is a top plan view of a structural fuse, according to an embodiment.

FIG. 1B is a top plan view of the structural fuse illustrated in FIG. 1A yielding.

FIG. 2A is a top plan view of a structural fuse that is an angle, according to an embodiment.

FIG. 2B is a cross-sectional schematic of the structural fuse taken along plane 2B-2B shown in FIG. 2A, according to an embodiment.

FIG. 3A is a top plan view of a structural fuse, according to an embodiment.

FIGS. 3B and 3C are top plan views of the structural fuse illustrated in FIG. 3A when the first load and the second load, respectively, are applied to the structural fuse, according to an embodiment.

FIG. 4A is a top plan view of a structural fuse, according to an embodiment.

FIGS. 4B and 4C are top plan views of the structural fuse illustrated in FIG. 4A when the first load and the second load, respectively, are applied to the structural fuse, according to an embodiment.

FIG. 5A is a side plan view of a component of a frame, according to an embodiment.

FIG. 5B is a cross-sectional schematic of the component taken along lines 5B-5B illustrated in FIG. 5A, according to an embodiment.

FIG. 6 is a side plan view of a portion of a frame, according to an embodiment.

FIG. 7 is a side plan view of a frame, according to an embodiment.

FIG. 8A is a side plan view of a frame, according to an embodiment.

FIG. 8B is a side plan view of the frame illustrated in FIG. 8A when a load is applied to the frame, according to an embodiment.

FIG. 9A is side plan view of a frame that does not include a structural fuse, according to an embodiment.

FIG. 9B is a side plan view of a frame that includes a structural fuse, according to an embodiment.

FIG. 10 is a side plan view of a portion of a frame, according to an embodiment.

FIG. 11 is a side plan view of a frame, according to an embodiment.

DETAILED DESCRIPTION

Embodiments are directed to structural fuses and connection systems including the same. An example structural fuse includes at least one plate. The structural fuse includes a plurality of cutouts formed in the plate. The cutouts are configured to cause at least one first yield region of the plate to yield when a first load is applied to the plate. In some embodiments, the plurality of cutouts are configured to cause at least one second yield region to yield when a second load is applied to the plate. At least a portion of the first yield region is distinct from at least a portion of the second yield region and the first load is different than the second load.

The structural fuses disclosed herein are configured to preferentially absorb and dissipate energy from a load by preferentially yielding. As used herein, “yield,” “yielding,” and “yielded” may refer to failing, fracturing, plastically deforming, or otherwise damaging an element (e.g., structural fuse) in a manner that may or may not require the replacement of the element after failure. Examples of loads that may cause yielding of the structural fuses includes loads caused by a seismic event or wind.

The structural fuses disclosed herein may be used in a frame (e.g., a moment-resisting frame, a beam-to-beam connection, a column-to-column connection, a beam-to-column connection, a frame including a collector, an eccentrically braced frame, a steel-plate shear wall building, etc.). The frame may include one or more generally horizontal beams, one or more generally vertical columns, one or more generally obliquely angled braces, a wall plate, or one or more connections that are configured to attach the beams, columns, braces, and/or wall plates together. The frame may form part of or an entirety of a structure (e.g., building). The structural fuses may absorb and dissipate some of the energy of loads applied to the frame which may prevent or avoid yielding of the other elements of the frame (e.g., beam, column, brace, plate wall, connections, etc.) that may otherwise result from the load. As such, the structural fuses

disclosed herein may move yielding from the other elements of the frame to the structure fuses to minimize yielding of the other components of the frame. The structural fuses disclosed herein may also be easier to replace after absorbing and dissipating energy from the load than if the other elements of the frame yielded. In other words, the structural fuses may limit the amount of load that may develop in the other elements of the frame thereby preventing damage to such other elements of the frame and making structures to such other elements of the frame easier to repair after the load is applied thereto. Further, the structural fuses disclosed herein are proportioned and positioned to yield such that large deformations may occur in the frame to absorb and dissipate energy from the load without losing strength in the structure that includes the frame. As such, the structural fuses disclosed herein may prevent the oversizing of the beams, columns, braces, and wall plates that may occur in a capacity based design and/or can be used to insert a plastic hinge location into the frame that would be otherwise disqualified for plastic design. Thus, the structural fuses may result in more economical design in some structures.

FIG. 1A is a top plan view of a structural fuse 100, according to an embodiment. The structural fuse 100 includes a single plate 102 that includes one or more connection regions 104 that are configured to be attached to other components of a frame, such as a beam and/or column. For illustrative purposes, the connection regions 104 of the plate 102 are illustrated in FIG. 1A using intersecting diagonal lines. The connection regions 104 may be configured to be attached to the other components of the frame using any suitable technique. In an example, as illustrated, the connection regions 104 may be configured to be connected to the other components of the frame using one or more bolts and nuts or rivets. In such an example, the connection regions 104 may define one or more holes 106 through which the bolts or rivets may be inserted. In an example, the connection regions 104 may be configured to be connected to the other components of the frame via welding. In such an example, the connection regions 104 of the plate 102 does not define one or more holes therein.

The structural fuse 100 includes at least one cutout 108 formed in the plate 102. The cutout 108 are configured to weaken the plate 102 such that the plate 102 yields in selected regions of the plate 102. For example, the cutout 108 is configured such that the plate 102 yields in one or more yield regions 110. At least a portion (e.g., majority or all) of the yield regions 110 are distinct from at least a portion (e.g., majority or all) of the connection regions 104. As such, failure of plastic deformation of the yield regions 110 of the plate 102 are unlikely to affect the connection between the plate 102 and the other elements of the frame to which the structural fuse 100 is attached. For illustrative purposes, the yield regions are illustrated in FIG. 1A using non-intersecting diagonal lines.

The plate 102 may include a top surface 112 and a bottom surface (not shown) opposite the top surface 112. In an embodiment, the cutout 108 may include an opening formed in the plate 102 that extends from the top surface 112 to the bottom surface. In other words, the cutout 108 may extend completely through the plate 102. When the cutout 108 extends completely through the plate 102, the cutout 108 is distinguishable from the holes 106 that are configured to receive the bolts or rivets by the size of the cutout 108. In an example, the cutout 108 exhibits a maximum lateral dimension or area that is significantly larger (e.g., at least 2 times larger, at least 5 times larger, or at least 10 times larger) than maximum lateral dimension or area the holes

106, respectively. In an example, the cutout 108 exhibits a maximum lateral dimension that is significantly larger (e.g., about 1.5 cm or greater, about 2 cm or greater, about 3 cm or greater, about 4 cm or greater, about 5 cm or greater, about 7.5 cm or greater, or 10 cm or greater) than the maximum lateral dimension of the holes 106. The cutout 108 may be significantly larger than the holes 106 since the cutout 108 is configured to selectively weaken the plate 102 whereas the holes 106 are configured to have a negligible effect on the strength of the plate 102. In an example, the cutout 108 may be distinguishable from the holes 106 because the cutout 108 exhibits a non-circular shape (e.g., elongated or square shape) while the holes 106 are circular. In an embodiment, the cutout 108 may extend from the top surface 112 to an intermediate location between the top surface 112 and the bottom surface. In other words, the cutout 108 may be a selectively thinned region of the plate 102.

The cutout 108 may extend inwardly from an edge 114 of the plate 102 or may be completely surrounded from the plate 102. In an example, the at least one cutout 108 may include a single cutout 108 that is completely surrounded by the plate 102. In an example, the at least one cutout 108 includes a single cutout 108 that extends inwardly from one edge 114 of the plate 102. In an example, the at least one cutout 108 includes a plurality of cutouts 108. In such an example, the plurality of cutouts 108 may extend inwardly from at least one edge 114 of the plate 102, be completely surrounded by the plate 102, or both (e.g., at least one cutout 108 extends inwardly from the edge 114 while at least one other cutout 108 is surrounded by the plate 102).

The cutout 108 may exhibit any suitable shape. Generally, the shape of the cutout 108 exhibits a generally rounded shape (e.g., circular or oblong shape) to prevent stress concentrators, which may cause the structural fuse 100 to fail or plastically deform at unsatisfactory low loads. However, the cutout 108 may exhibit a non-rounded shape, such as a rectangular or square shape. The stress concentrators (e.g., corners) of such non-rounded shapes may allow for more control of which portions of the plate 102 are the yield regions 110. In an example, the cutout 108 may exhibit a longitudinally extending shape, such as an oblong, ellipsoid, or rectangular shape. The longitudinally extending shape may weaken region of the plate 102 that are aligned with the longitudinal axis of the longitudinally extending shape of the cutout 108 thereby allowing for more control of which portions of the plate 102 are the yield region 110. That is, the yield regions 110 are the portions of the plate 102 that are aligned with the longitudinal axis of the cutout 108.

As previously discussed, the at least one cutout 108 may include a plurality of cutouts 108. In an embodiment, at least some of the plurality of cutouts 108 may be arranged on the plate 102 in a generally straight line. Arranging the plurality of cutouts 108 in a generally straight line causes the yield region 110 to be aligned and positioned on the generally straight line. In other words, the yield region 110 is located between the plurality of cutouts 108 arranged in the straight line. As such, arranging the plurality of cutouts 108 in a generally straight line may allow for better control of which portions of the plate 102 that are yield region 110. However, as illustrated in FIGS. 3A-3C, at least one of the plurality of cutouts 108 may not be arranged in a generally straight line.

As previously discussed, the plate 102 includes at least one yield region 110. The yield region 110 includes portions of the plate 102 that are weakened by the cutout 108 such that the yield region 110 preferentially yield when a load is applied to the plate 102. In an example, the at least one cutout 108 includes a plurality of cutouts 108 and the yield

region 110 is between adjacent ones of the cutouts 108. In such an example, the yield region 110 is between the adjacent cutouts 108 because the adjacent cutouts 108 weaken a portion of the plate 102 between the cutouts 108.

5 In an example, shown in FIGS. 2A-4C, the yield region 110 is between the cutout 108 and an edge 114 of the plate 102. For instance, the yield region 110 is between the cutout 108 and the edge 114 nearest the cutout 108.

The plate 102 may exhibit a major axis 116. The major 10 axis 116 is generally aligned with a longitudinal axis of the beam or column to which the plate 102 is attached. Additionally or alternatively, the major axis 116 of the plate 102 may be the longitudinal axis of the plate when the plate 102 includes a longitudinal axis (e.g., the plate 102 is not square or circular). The yield region 110 may extend from the cutout 108 is an angle that is generally parallel to, generally perpendicular to, or oblique relative to the major axis 116 of the plate 102.

The direction that the yield region 110 extends from the 20 cutout 108 effects which load applied to the structural fuse causes the yield region 110 to yield. For example, only loads that are generally parallel to the direction that the yield region 110 extends from the cutout 108 may cause the yield region 110 to yield. When a load is applied to the structural 25 fuse 100 that is obliquely angled relative to the yield region 110, the obliquely angled load may be broken into a first load component that is generally parallel to the direction that the yield region 110 extends from the cutout 108 and a second load component that is perpendicular to the first load. The 30 first load component may cause the yield region 110 to yield while the second load component is unlikely to cause the yield region 110 to yield.

Referring to FIG. 1B, which is a top plan view of the structural fuse 100 yielding, a load L may be applied to the 35 structural fuse 100. The load L may be applied to the structural fuse 100 responsive to a load (e.g., seismic or wind load) being applied to a frame that includes the structural fuse 100. The load L is illustrated to be generally parallel to the major axis 116 and the direction that the yield 40 region 110 extends from the cutout 108. The load L is sufficiently large to cause the plate 102 to yield at the yield regions 110 thereof since the load L is generally parallel to the direction that the yield region 110 extends from the 45 cutout 108. The yielded yield regions 110 of the plate 102 are illustrated in FIG. 1B as being diagonal non-intersecting lines. Yielding the yield regions 110 of the plate 102 causes the structural fuse 100 to absorb and dissipate at least some of the energy from the load applied to the frame that includes the structural fuse 100, thereby decreasing the likelihood that other components of the frame yield in response to the load. Since the yield regions 110 are at least partially distinct from the connection regions 104, the load L does not cause the connection regions 104 of the plate 102 to yield which 50 may adversely affect the attachment between the structural fuse 100 and the components of the frame to which the structural fuse 100 is attached.

The load L illustrated in FIG. 1B is a shear force that is generally parallel to the major axis 116 of the plate 102. However, the load L that causes the yield region 110 to yield may include a shear force that is not generally parallel to the major axis (as shown in FIGS. 3C and 4C); a tensile load that is parallel, perpendicular, or obliquely angled relative to the major axis 116; a compressive load, a bending moment, or any other load.

60 Referring back to FIG. 1A, the plate 102 may exhibit any suitable shape prior to the yield region 110 yielding. The shape of the plate 102 may be selected to minimize the size

and weight of the structural fuse 100 while also allowing the structural fuse 100 to be attached to components to the frame. In an example, as illustrated, the plate 102 exhibits a generally rectangular shape. In an example, the plate 102 may exhibit a generally top-hat shape that includes a first rectangle and a second rectangle extending therefrom wherein width of the first rectangle is less than a width of the second rectangle. The generally top-hat shape of the plate 102 may allow the first rectangle to be attached to a flange of a beam while the second rectangle extends outwardly from the flange of the beam thereby facilitating attachment to an angle that is attached to a column (i.e., the structural fuse 100 forms part of a beam-to-column connection system). Examples of such connection is disclosed in U.S. Pat. No. 10,361,507 filed on Apr. 24, 2017, the disclosure of which is incorporated herein, in its entirety, by this reference. In an example, the plate 102 may exhibit a generally L-shape cross-section (as shown in FIGS. 2A-2C), a generally I-shaped cross-section (as shown in FIGS. 5A and 5B), or any other suitable shape.

As previously discussed, the structural fuses disclosed herein may exhibit a generally L-shaped cross-section. In other words, the structural fuses disclosed herein may be an angle. For example, FIG. 2A is a top plan view of a structural fuse 200 that is an angle, according to an embodiment. FIG. 2B is a cross-sectional schematic of the structural fuse 200 taken along plane 2B-2B shown in FIG. 2A, according to an embodiment. Except as otherwise disclosed herein, the structural fuse 200 may be the same or substantially similar to any of the structural fuses disclosed herein. For example, the structural fuse 200 may include at least one plate 202 that includes at least one connection region 204 (illustrated in FIG. 2A using intersecting diagonal lines), at least one cutout 208 formed in the plate 202, and at least one yield region 210 (illustrated in FIG. 2A using non-intersecting diagonal lines).

The plate 202 of the structural fuse 200 may be an angle. For example, the plate 202 may include a first section 218 and a second section 220. The first and second planar sections 218, 220 are illustrated as being generally planar though the first and second planar sections 218, 220 may be bent or curved. The first section 218 may be oriented at a perpendicular or oblique (e.g., acute or obtuse) angle relative to the second section 220 such that the plate 202 exhibits a generally L-like cross-sectional shape. In an embodiment, as illustrated, the first and second sections 218 are formed from two distinct plates that are attached (e.g., welded) together. In an embodiment, the plate 202 is formed from a single piece of material that is bent, extruded, or otherwise shaped to form the first and second sections 218, 220.

At least one of the first or second section 218, 220 may include at least one cutout 208 formed therein. For example, as shown in FIG. 2B, each of the first and second sections 218, 220 include at least one cutout 208 formed therein. The cutout 208 may be same or substantially similar to any of the cutouts disclosed herein and may be configured to form at least one yield region 210. The yield region 210 may extend between adjacent cutouts 208 and/or the edges 214 of the plate 202. As illustrated, the at least one cutout 208 of the structural fuse 200 forms yield regions 210 that are distinct from the connection regions 204 of the plates 202.

The structural fuses illustrated in FIGS. 1A-2B include at least one yield region that extends from the at least one cutout thereof in a single direction. As previously discussed, the yield region(s) of such structural fuses may yield when a load (or component of the load) is applied to the structural fuses that is generally parallel to the direction that the yield

region(s) extend from the cutout. Thus, the structural fuses illustrated in FIGS. 1A-2B may absorb energy from a load applied to the structural fuses when the load or a component of the load is generally parallel to the direction that the yield regions extend from the cutouts. However, in an example, the load applied to the structural fuses in response to the load being applied to the frame is likely to vary such that the direction of the load applied to the structural fuses may not always be generally parallel to the direction that the yield regions extend from the cutouts. In such an example, the entire load or a component of the load may not be absorbed and dissipated by the structural fuse.

As such, in some embodiments, the structural fuses disclosed herein may be configured to include at least one first yield region that is configured to yield when a first load is applied to the structural fuse and at least one second yield region that is configured to yield when a second load is applied to the structural fuse. The first load and the second load are different from each other. For example, the first load and the second load may be at least one of different types of loads (e.g., shear and tensile loads), the same type of load applied at different directions to the structural fuse (e.g., parallel and perpendicular to the major axis of the structural fuse), or different components of the same load. FIGS. 3A to 4C illustrate structural fuses that include first and second yield regions that are configured to preferentially yield when two different loads are applied to the structural fuses.

FIG. 3A is a top plan view of a structural fuse, 300, according to an embodiment. Except as otherwise disclosed herein, the structural fuse 300 is the same or substantially similar to any of the structural fuses disclosed herein. For example, the structural fuse 300 includes at least one plate 302. The structural fuse 300 also includes at least one connection region 304 (illustrated using intersecting diagonal lines), a plurality of cutouts, and a plurality of yield regions (illustrated using non-intersecting diagonal lines).

The plurality of cutouts includes at least one first cutout 308a and at least one second cutout 308b and the plurality of yield regions includes at least one first yield region 310a and at least one second yield region 310b. The first cutout 308a is configured to form the first yield region 310a when a first load L1 (shown in FIG. 3B) is applied to the structural fuse 300. The second cutout 308a is configured to form the second yield region 310b when a second load L2 (shown in FIG. 3C) is applied to the structural fuse 300. It is noted that, optionally, the first cutout 308a may facilitate the formation of the second yield region 310b when the second load L2 is applied to structural fuse 300 and/or the second cutout 308b may facilitate the formation of the first yield region 310a when the second load L2 is applied to the structural fuse 300.

In the illustrated embodiment, the at least one first yield region 310a extends from the first cutout 308a in a first direction. The first direction is illustrated as being generally parallel to the major axis 316 of the plate 302 though the first direction may be oblique or perpendicular to the major axis 316. The first yield region 310a may extend from the first cutout 308a in the first direction because, for example, the first cutout 308a exhibits an elongated shape and the longitudinal axis of the elongated shape extends in the first direction. The direction that the first yield regions 310a extends from the first cutout 308a allows the first yield regions 310a to preferentially yield when the first load L1 is parallel to the first direction. As previously discussed, the first load L1 may be an entirety of a load applied to the structural fuse 300 or may be a component of a load that is generally parallel to the first direction when the load that forms the first load L1 is parallel or obliquely angled,

respectively, to the first direction. The first cutout **308a** is configured to cause the first yield regions **310a** to extend therefrom in a direction that is generally parallel to the first direction by weakening the portions of the plate **302** that forms the first yield region **310a**. In an example, as illustrated, the first cutout **308a** may weaken a portion of the plate **302** that extends from the first cutout **308a** to an edge **314** (e.g., a cross-wise edge) of the plate **302**. In such an example, the first cutout **308a** is spaced from the edge **314** and there is no additional first cutout **308a** extending inwardly from the edge **314**. In an example, as illustrated, the first cutout **308a** and the second cutout **308a** may weaken a portion of the plate **302** that extends from the first cutout **308a** to the second cutout **308b** in a direction that is generally parallel to the first direction. In an example, not shown, the first cutout **308a** may extend inwardly from the edge **314** and/or the first cutout **308a** may include a plurality of first cutouts **308a** that are arranged in a line, as previously discussed with regards to the cutouts illustrated in FIGS. 1A-2B. In such an example, the first yield region **310a** may extend from such first cutouts **308a** in a direction that is generally parallel to the first direction.

In an embodiment, the first yield region **308a** may include a plurality of first yield regions **310a** that are arranged in a line that is generally parallel to the first direction. In an embodiment, the first yield region **310a** may include a plurality of first yield regions **310a** that form two or more lines that are each generally parallel to the first direction. In such an embodiment, the two or more lines of the first yield regions **310a** may facilitate yielding caused by a tensile load than if the plurality of first yield regions **310a** were arranged in a single line.

In the illustrated embodiment, the at least one second yield region **310b** extends from the second cutout **308b** in a second direction that is different than the first direction. The second direction is illustrated as being generally perpendicular to the major axis **316** of the plate **302** through, it is noted, the second direction may be oblique or perpendicular to the major axis **316**. The second yield region **310b** may extend from the second cutout **308b** in the second direction because, for example, the second cutout **308b** exhibits an elongated shape and the longitudinal axis of the elongated shape extends in the second direction. The second yield regions **310b** extending from the second cutout **308b** in the second direction allows the second yield regions **310b** to preferentially yield when the second load **L2** is parallel to the second direction. As previously discussed, the second load **L2** may be an entirety of a load applied to the structural fuse **300** or may be a component of a load that is generally perpendicular to the second direction when the load that forms the second load **L2** is perpendicular or obliquely angled, respectively, to the second direction. The second cutout **308b** is configured to cause the second yield regions **310b** to extend therefrom in a direction that is generally parallel to the second direction by weakening the portions of the plate **302** that forms the second yield region **310b**. In an example, as illustrated, the second cutout **308b** may weaken a portion of the plate **302** that extends from the second cutout **308b** to an edge **314** (e.g., a longitudinal edge) of the plate **302**. In such an example, the second cutout **308b** is spaced from the edge **314** and there is no additional second cutout **308b** extending inwardly from the edge **314**. In an example, not shown, the second cutout **308b** may extend inwardly from the edge **314** and/or the second cutout **308b** may include a plurality of second cutouts **308b** that are arranged in lines, as previously discussed with regards to the cutouts illustrated in FIGS. 1A-2B. In an embodiment,

similar to the first cutout **308a**, the second cutout **308b** may include a plurality of second cutouts **308b** arranged in one or two or more lines.

FIGS. 3B and 3C are top plan views of the structural fuse **300** when the first load **L1** and the second load **L2**, respectively, are applied to the structural fuse **300**, according to an embodiment. Referring to FIG. 3B, the first load **L1** may be applied to the structural fuse **300**. As previously discussed, the first load **L1** may be generally parallel to the first direction of the structural fuse **300**. The first load **L1**, when sufficiently large, may cause the first yield regions **310a** to yield. For illustrative purposes, the yielded first regions **310a** are illustrated using diagonal lines. In an embodiment, as shown, the first load **L1** is a tensile load. The first load **L1** may be a tensile load when the connection regions **304** are spaced from each other in the first direction and the components of the frame to which the connection regions **304** are attached move apart from each other. When the first cutouts **308a** are arranged in two lines, the tensile first load **L1** may cause the yield regions **310a** to elongated, as shown. However, it is noted that the first load **L1** may be a compressive load, a shear load, or any other type of load applied to the structural fuse **300**.

Referring to FIG. 3C, the second load **L2** may be applied to the structural fuse **300**. As previously discussed, the second load **L2** may be generally parallel to the second direction. The second load **L2**, when sufficiently large, may cause the second yield regions **310b** to yield. For illustrative purposes, the yielded second yield regions **310b** are illustrated using diagonal lines. In an embodiment, as shown, the second load **L2** is a shear load. The second load **L2** may be a shear load when the connection regions **304** are spaced from each other in the first direction and the components of the frame to which the connection regions **304** are attached move sideways relative to each other. However, it is noted that the second load **L2** may be a compressive load, a shear load, or any other type of load applied to the structural fuse **300**.

Unlike the structural fuses illustrated in FIGS. 1A-2B, the structural fuse **300** may absorb and dissipate energy from two different loads, namely the first load **L1** and the second load **L2**. For example, the structural fuses illustrated in FIGS. 1A-2B may only be able to absorb and dissipate energy from one of the first load **L1** or the second load **L2**. The other of the first load **L1** or second load **L2** that is not absorbed by such structural fuses may be absorbed and dissipated by other components of the frame or by portions of such structural fuses that are not yield regions (e.g., the connection region). Yielding in portions of the frame other than the yield regions of the structural fuses may cause catastrophic failure of the frame, oversizing the elements of the frame, forming plastic hinges, or require complex and/or difficult repairs. However, the structural fuse **300** may be able to absorb and dissipate the energy from both the first and second loads **L1**, **L2** thereby decreasing the likelihood that the frame fails, the frame needs oversized elements, or plastic hinges and/or may facilitate repair of the frame.

FIG. 4A is a top plan view of a structural fuse **400**, according to an embodiment. Except as otherwise disclosed herein, the structural fuse **400** is the same or substantially similar to any of the structural fuses disclosed herein. For example, the structural fuse **400** includes at least one plate **402**. The plate **402** includes one or more connection region **404** (illustrated using intersecting diagonal lines), a plurality of cutouts, and a plurality of yield regions (illustrated using non-intersecting diagonal lines). The structural fuse **400** is

11

configured to absorb and dissipate energy from a first load L1 (shown in FIG. 4B) and a second load L2 (shown in FIG. 4C).

The plurality of cutouts includes at least one first cutout 408a and at least one second cutout 408b. The plurality of yield region include a plurality of first yield regions 410a and one or more second yield regions 410b. The first cutout 408a and the second cutout 408b are both configured to form the first yield regions 410a and the second yield regions 410b. The first yield regions 410a are configured to extend from the first and the second cutouts 408a, 408b in a first direction and the second yield regions 410b are configured to extend from the first and second cutouts 408a, 408b in a second direction that is different than the first direction. In an example, as shown, the first and second directions are generally parallel and perpendicular, respectively, to the major axis 416 of the plate 402. As such, the structural fuse 400 may be configured to absorb and dissipate energy in response to two different loads, such as the first load L1 and the second load L2.

The first cutout 408a and the first yield regions 410a extending therefrom are arranged in a first line that is generally parallel to the first direction. The second cutout 408a and the first yield regions 410a extending therefrom are arranged in a second line that is generally parallel to the first direction and offset relative to the first line. As such, the first and second cutouts 408, 408b weaken portions of the plate 402 between adjacent ones of the cutouts and/or cutouts and the edges 414 (e.g., cross-wise edges) of the plate 402. In an embodiment, the first and second cutouts 408a, 408b may exhibit longitudinal shapes and the longitudinal axes of the longitudinal shapes are aligned parallel to the first direction.

The first cutout 408a and the second cutout 408b are arranged on the first and second lines such that a portion of the first cutout 408b overlaps (in the second direction) with a portion of one or more of the second cutout 408b and vice versa. The second yield regions 410b extend between the overlapping portions of the first and second cutouts 408a, 408b. In other words, the first and second cutouts 408a, 408b weaken portions of the plate 402 between the overlapping portions of the first and second cutouts 408a, 408b.

FIGS. 4B and 4C are top plan views of the structural fuse 400 when the first load L1 and the second load L2, respectively, are applied to the structural fuse 400, according to an embodiment. Referring to FIG. 4B, the first load L1 is applied to the structural fuse 400. The first load L1 may be generally parallel to the first direction (e.g., generally parallel to the major axis 416). The first load L1 is illustrated as being a shear load but, it is noted, the first load L1 may be a tensile load or any other type of load. The first load L1 causes the first yield regions 410a to yield. For illustrative purposes, the yielded yield regions 410a are illustrated using diagonal lines,

Referring to FIG. 4C, the second load L2 is applied to the structural fuse 400. The second load L2 is different than the first load L1. For example, the second load L2 is applied to the structural fuse 400 in the second direction and is perpendicular to the first direction. The second load L2 is illustrated as being a tensile load but, it is noted, the second load L2 may be a shear load or any other type of load. The second load L2 causes the second yield regions 410b to yield. For illustrative purposes, the yielded yield regions 410a are illustrated using diagonal lines.

In some embodiment, the structural fuses illustrated in FIGS. 1A-4C are formed using one or more plates that are distinct from the other components of the frame, such as

12

beams, columns, braces, etc. In such embodiments, the structural fuses may connect the other components of the frame. However, the structural fuses disclosed herein may be formed in one or more plates that are integrally formed with the other components of the frame. For example, the structural fuses disclosed herein may form at least a portion of the beams, columns, braces, wall plates, or other components of the frame. FIG. 5A is a side plan view of a component 521 of a frame (not shown), according to an embodiment. FIG. 5B is a cross-sectional schematic of the component 521 taken along lines 5B-5B illustrated in FIG. 5A, according to an embodiment.

The component 521 is formed from one or more plates. In an example, as illustrated, the component 521 is illustrated as an I-beam and the plates of the component 521 includes two flanges 522 and a web 524 extending between the two flanges 522. The flanges 522 and the web 524 may be attached together (e.g., via welding) or integrally formed (e.g., extruded). In an example, the component 521 may be a hollowed structural section beam, an L-beam, a T-beam, a channel, or any other structure used in frames. In such an example, the flanges, webs, etc. of such components form the plates of the component 521. In an embodiment, as illustrated, the component 521 may be configured to be attached to another component of the frame, such as a plate that attached the component 521 to a beam or column. In such an embodiment, the component 521 may define one or more holes 506 when the component 521 is attached to the other component using bolts.

One or more of the plates of the component 521 (e.g., one or more of the two flanges 522 or the web 524) defines at least one cutout 508. In the illustrated embodiment, the cutout 508 defined by the plate of the component 521 are arranged in the same manner as the cutouts illustrated in FIG. 3A. However, the cutout 508 may be arranged according to any of the embodiments disclosed herein. The cutout 508 formed on the plate of the component 521 forms yield regions that preferentially yield when a load is applied to the component 521. As such, the plate of the component 521 absorbs and dissipate energy. The other plate(s) of the component 521 that do include at least one cutout may not yield when the load is applied to the component 521 thereby maintaining at least some of the strength of the component.

As previously discussed, the structural fuses disclosed herein form part of frames. FIGS. 6-11 illustrate at least a portion of different frames that may include the structural fuses disclosed herein. FIG. 6 is a side plan view of a portion of a frame 630, according to an embodiment. The frame 630 includes a first beam 632 and a second beam 634. The first beam 632 is illustrated as an I-beam that includes two flanges 622a and a web 624a extending therebetween. The second beam 634 is also illustrated as an I-beam that includes two flanges 622b and a web 624b extending therethrough. It is noted that at least one of the first or second beam 632, 634 may include a hollowed structural sectioned beam or any other structural beam. The first beam 632 includes a first terminal end 636 and the second beam 634 includes a second terminal end 638 positioned adjacent to the first terminal end 636 of the first beam 632.

The first and second beams 632, 634 are attached together using a beam-to-beam connection system 650. The beam-to-beam connection system 650 includes at least one of a first plate 640 or a second plate 642. The first plate 640 may be attached to adjacent flanges 622a, 624b of the first and second beams 632, 634. The second plate 642 may be attached to adjacent flanges 622a, 624b of the first and second beams 632, 634 that are opposite the flanges 622a,

624b of the first and second beams 632, 634 that are attached to the first plate 640. The first and second plates 640, 642 are illustrated as being attached to the first and second beams 632, 634 using one or more bolts 662. However, the first and second plates 640, 642 may be riveted, welded, or otherwise attached to the first and second beams 632, 634.

At least one of the first or second plate 640, 642 may be any of the structural fuses disclosed herein. For example, at least one of the first or second plate 640, 642 may define at least one cutout that is configured to form one or more yield regions. In an embodiment, both the first and second plates 640, 642 are the structural fuses or only the first plate 640 is the structural fuse. In an embodiment, only the second plate 642 is the structural fuse. In such an embodiment, only the second plate 642 may be the structural fuse when a floor is formed on the frame 630 such that the floor is formed over the first plate 640. The floor may make accessing and repairing the first plate 640 difficult. However, the second plate 642 may be accessed and repaired through the ceiling which may be significantly easier than accessing and repairing the first plate 640 through the floor.

The first and second plates 640, 642 may be attached to the web 624a, 624b of the first and second beams 632, 634 instead of or in addition to the flanges 622a, 622b. For example, FIG. 7 is a side plan view of a frame 730, according to an embodiment. Except as otherwise disclosed herein, the frame 730 is the same or substantially similar to the frame 630 illustrated in FIG. 6. For example, the frame 730 includes a first beam 732 and a second beam 734. The first beam 732 may be an I-beam that includes two flanges 722a and a web 724a extending between the two flanges 722a. The second beam 734 may also be an I-beam that includes two flanges 722b and a web 724b extending between the two flanges 722b. However, at least one of the first or second beam 732, 734 may include a hollowed sectional structural beam or another type of structural beam. The frame 730 also includes a beam-to-beam connection system 750 that includes at least one plate 740. The plate 740 may be attached to the webs 724a, 724b of the first and second beams 732, 734. The plate 740 may be the same or substantially similar to any of the structural fuses disclosed herein. For example, as illustrated, the plate 740 may be the same or substantially similar to the structural fuse 300 illustrated in FIG. 3A.

FIG. 8A is a side plan view of a frame 830, according to an embodiment. The frame 830 includes a first column 844 and a second column 846. The first and second columns 844, 846 are illustrated as being attached to a surface 848 (e.g., ground, foundation, or another portion of the structure that includes the frame 830). The frame 830 includes a first beam 832 attached to and extending from the first column 844 and a second beam 832 attached to and extending from the second column 846. The first and second beams 832, 834 may be attached together using a beam-to-beam connection system 850. The beam-to-beam connection system 850 may be the same or substantially similar to any of the beam-to-beam connection systems disclosed herein. In other words, the beam-to-beam connection system 850 includes at least one structural fuse that is the same or substantially similar to any of the structural fuses disclosed herein. It is noted that, in an example, the first and second beam 832, 834 may be integrally formed together and the beam-to-beam connection system 850 is replaced with the structural fuse illustrated in FIG. 5A. The frame 830 may also include a brace 852 extending from a portion of the first column 844 that is spaced from the first beam 832 to a portion of the first beam 832 that is spaced from the first column 844. For example,

the brace 852 may extend from a portion of the first column 844 that is at or near the first surface 848 to a portion of the first beam 832 that is at or near the beam-to-beam connection system 850.

FIG. 8B is a side plan view of the frame 830 illustrated in FIG. 8A when a load L is applied to the frame 830, according to an embodiment. The frame 830 and in particular the beam-to-beam connection system 850 with the structural fuse may allow precise control of the axial load transfer between the first and second beams 832, 834. Under the load F, the structural fuses of the beam-to-beam connection system 850 may yield in the longitudinal direction thereby preventing overload in the first and second beams 832, 834 and the brace 852. In other words, the beam-to-beam connection system 850 moves the yielding of the frame 830 from the first and second beams 832, 834 and the brace 852 (which is where the yielding would occur without the structural fuses) to the structural fuse(s) of the beam-to-beam connection system 850. The structural fuses of the beam-to-beam connection system 850 are much easier to replace than any one of the first beam 832, the second beam 834, or the brace 852.

FIG. 9A is side plan view of a frame 930a that does not include a structural fuse, according to an embodiment. The frame 930a includes a first column 944, a second column 946, and a third column 954. The first, second, and third columns 944, 946, 954 are illustrated as being attached to a surface 948. The frame 930a includes a first beam 932 attached to and extending between the first and second columns 944, 946. The frame 930a includes a brace 952 extending between at least two of the first beam 932, the first column 944, the second column 946, or the surface 948. The first beam 932, the first column 944, the second column 946, and the brace 952 may form a lateral frame 956. The frame 930a also includes a second beam 934a attached to and extending between the second and third columns 946, 954. The second beam 934a may be known as a "collector" since it transmits a load L to the lateral frame 956. Transferring the load L to the lateral frame 956 may cause one or more components of the lateral frame 956, and in particular the brace 952, to yield. As such, the lateral frame 956 may be subjected to oversizing to prevent yielding of the components thereof or may require costly and difficult repairs to repair the yielded components.

FIG. 9B is a side plan view of a frame 930b that includes a structural fuse, according to an embodiment. Except as otherwise disclosed herein, the frame 930b is the same or substantially similar to the frame 930a illustrated in FIG. 9A. For example, the frame 930b includes a lateral frame 956 that includes a first beam 932, a first column 944, a second column 946, and a brace 952. The frame 930b also includes a third column 954. However, instead of the single second beam 934a illustrated in FIG. 9A, the frame 930b includes one or more second beams 934b attached to and extending between second column 946 and the third column 954. The one or more second beams 934b may include a beam with a structural fuse formed therein (as illustrated in FIG. 5A) and/or a plurality of beams attached together using a beam-to-beam connection system 950 that includes one or more structural fuses. When the load L is applied to the frame 930b, the structural fuse of the second beam 934b (e.g., the structural fuse formed in the second beam 934b and/or the beam-to-beam connection system 950) may yield. In other words, yielding the structural fuse of the second beam 934b may absorb and dissipate energy that may otherwise cause the brace 952 or another component of the lateral frame 956 to yield. Repairing the frame 930b may be

15

easier when the structural fuse of the second beam **934b** yields, especially when the structural fuse forms part of the beam-to-beam connection system **950**, than when the components of the lateral frame **956** yield.

FIG. 10 is a side plan view of a portion of a frame **1030**, according to an embodiment. The frame **1030** includes a beam **1032**. The beam **1032** is illustrated as being an I-beam that includes a top flange **1022a**, a bottom flange **1022b**, and a web **1024** extending between the top and bottom flanges **1022a**, **1022b**. However, it is noted that the beam **1032** may include a hollowed structural sectional beam, a T-beam, or any other type of structural beam. The frame **1030** also includes a column **1044**. The column **1044** is illustrated as being an I-beam that includes a first flange **1058a**, a second flange **1058b**, and a web **1060** extending between the first and second flanges **1058a**, **1058b**. However, similar to the beam **1032**, the column **1044** may include a hollowed structural sectional beam a T-beam, or any other type of structural beam.

The beam **1032** may be attached to the first flange **1058a** of the column **1044** using a beam-to-column connection system **1050**. The beam-to-column connection system **1050** includes a first plate **1040** and a second plate **1042** attached to the first flange **1058a** of the column **1044**. The first and second plates **1040**, **1042** may be attached to the first flange **1058** using welding, bolts, rivets, or any other technique. The first plate **1040** is configured to be attached to the top flange **1022a** of the beam **1032** using one or more bolts **1062** or any other attachment technique. In the illustrated embodiment, the first plate **1040** is directly attached to the top flange **1022a** though, in some embodiments, the first plate **1040** may be indirectly attached to the top flange **1022a**, such as via at least one additional plate. The second plate **1040** is configured to be attached, either directly or indirectly, to the bottom flange **1022b** of the beam **1032** using any suitable technique. In the illustrated embodiment, when the second plate **1040** is indirectly attached to the bottom flange **1022b**, the beam-to-column connection system **1050** includes a third plate **1064** directly attached (e.g., welded, bolted, etc.) to the bottom flange **1022b** of the beam **1032**. The third plate **1064** may be attached to the second plate **1042** using one or more bolts **1062**, welding, or any other attachment technique. The beam **1032** may define a cutout **1066** that is configured to receive the second plate **1042**. In some embodiments, the beam-to-column connection system **1050** also includes a shear tab **1068** attached to the first flange **1058a** of the column **1044** and the web **1026** of the beam **1032**.

One or more of the first plate **1040**, the second plate **1042**, or the third plate **1064** is a structural fuse (e.g., defines at least one cutout configured to form yield regions). For example, the third plate **1064** may include the structural fuse since the third plate **1064** may be easier to replace than the first or second plates **1040**, **1042**. The structural fuse may limit bending moments in the beam-to-column connection system **1050** and can prevent yielding of the beam **1032** and the column **1044** when a load (not shown) is applied to the frame **1030**. Further, the structural fuse may change the governing limit state for the beam **1032**, if necessary, so that plastic design procedures can be used in the frame **1050**.

FIG. 11 is a side plan view of a frame **1130**, according to an embodiment. In particular, the frame **1130** is a plate shear wall, such as a steel plate shear wall. The frame **1130** includes two column **1144** spaced from each other. The frame **1130** also includes two beams **1132** extending between the two columns **1144** that are spaced from each other. The beams **1132** may be attached to the columns **1144**

16

using any suitable technique, such as the beam-to-column connection system **1050** illustrated in FIG. 10 or any conventional means. The frame **1130** also includes a plate wall **1170** positioned in the space between the two beams **1132** and the two columns **1144**. The plate wall **1170** may be formed from steel or any other suitable material.

The frame **1130** may include one or more mounts **1172** that are each attached to the plate wall **1170** and one of the beams **1132** or the columns **1144**. For example, in the illustrated embodiment, the frame **1130** includes four mounts **1172** and each of the mounts **1172** are attached to one of the beams **1132** or the columns **1144** and the wall plate **1170**. Each of the mounts **1172** may include a planar plate and/or an angle (i.e., an L-shaped beam). It is noted that attaching the plate wall **1170** to the beams **1132** and the columns **1144** with the mounts **1172** may decrease the cost of forming the shear plate wall than if the plate wall **1170** was attached to the beams **1132** and the columns **1144** using conventional techniques. At least one of the mounts **1172** is a structural fuse. That is, at least one of the mounts **1172** includes at least one cutout formed therein that form one or more yield regions.

A load applied to a conventional plate shear wall (e.g., a plate shear wall without a structural fuse) may cause the steel plate wall thereof to yield. Repairing the yielded steel plate wall is very difficult. However, a load applied to the frame **1130** may cause one or more of the mounts **1172** to yield instead of the plate wall **1170**. Repairing the yielded mounts **1172** may be significantly easier and less expensive than repairing the plate wall **1170**.

Further examples of connection systems (e.g., beam-to-beam and beam-to-column connection systems) that may use any of the structural fuses disclosed herein are disclosed in U.S. Provisional Patent Application No. 63/174,663 filed on Apr. 14, 2021, U.S. Pat. No. 10,689,876 filed on Aug. 10, 2018, U.S. Pat. No. 10,584,477 filed on Apr. 25, 2019, U.S. Pat. No. 10,316,507 filed on Aug. 26, 2015, U.S. Pat. No. 10,760,261 filed on Dec. 8, 2016, and International Application No. WO 2021/030111 filed on Aug. 5, 2020, the disclosures of each of which are incorporated herein, in its entirety, by this reference.

While various aspects and embodiments have been disclosed herein, other aspects and embodiments are contemplated. The various aspects and embodiments disclosed herein are for purposes of illustration and are not intended to be limiting.

Terms of degree (e.g., “about,” “substantially,” “generally,” etc.) indicate structurally or functionally insignificant variations. In an example, when the term of degree is included with a term indicating quantity, the term of degree is interpreted to mean $\pm 10\%$, $\pm 5\%$, or $\pm 2\%$ of the term indicating quantity. In an example, when the term of degree is used to modify a shape, the term of degree indicates that the shape being modified by the term of degree has the appearance of the disclosed shape. For instance, the term of degree may be used to indicate that the shape may have rounded corners instead of sharp corners, curved edges instead of straight edges, one or more protrusions extending therefrom, is oblong, is the same as the disclosed shape, etc.

60 What is claimed is:

1. A structural fuse, comprising:
at least one plate;
at least one first cutout located in a first portion of the at least one plate, the at least one first cutout partially defining at least one first yield region, the at least one first yield region configured to yield upon application of a first load to the plate; and

17

at least one second cutout located in a second portion of the at least one plate, the at least one second cutout partially defining at least one second yield region, the at least one second yield region configured to yield upon application of a second load to the plate, wherein a substantial portion of the at least one first yield region is distinct from a substantial portion of the at least one second yield region;

wherein the first load is different from the second load.

2. The structural fuse of claim 1, wherein the at least one plate includes a single plate.

3. The structural fuse of the claim 1, wherein the at least one plate includes a plurality of plates attached together to form an angle.

4. The structural fuse of claim 1, wherein the at least one plate includes two flanges and a web extending therebetween.

5. The structural fuse of claim 1, wherein the at least one first yield region is between the at least one first cutout and an edge of the at least one plate.

6. The structural fuse of claim 1, wherein the at least one first yield region is between the at least one first cutout and the at least one second cutout.

7. The structural fuse of claim 1, wherein the at least one second cutout includes a plurality of second cutouts and the at least one second yield region is between adjacent ones of the plurality of cutouts.

8. The structural fuse of claim 1, wherein the at least one plate includes at least one first attachment region and at least one second attachment region.

9. The structural fuse of claim 8, wherein at least a portion of the at least one first yield region and the at least one second yield region are distinct from at least a portion of the first attachment region and the second attachment region.

10. The structural fuse of claim 1, each of the at least one first cutout and the at least one second cutout exhibits an elongated shape.

11. The structural fuse of claim 10, wherein a longitudinal axis of the at least one first cutout extends in a first direction and a longitudinal axis of the at least one second cutout extends in a second direction.

12. The structural fuse of claim 10, wherein a longitudinal axis of the at least one first cutout and a longitudinal axis of the at least one second cutout are substantially parallel.

13. A frame, comprising:

a first component;

a second component; and

a connection system attaching the first component to the second component, the connection system including at least one structural fuse, the at least one structural fuse including:

at least one plate;

at least one first cutout located in a first portion of the

at least one plate, the at least one first cutout partially defining at least one first yield region, the at least one first yield region configured to yield upon application of a first load to the plate; and

18

at least one second cutout located in a second portion of the at least one plate, the at least one second cutout partially defining at least one second yield region, the at least one second yield region configured to yield upon application of a second load to the plate, wherein a substantial portion of the at least one first yield region is distinct from a substantial portion of the at least one second yield region;

wherein the first load is different from the second load; wherein the first component and the second component are independently selected from a beam, a column, or a wall plate.

14. A frame, comprising:

a first component;

a second component; and

a connection system attaching the first component to the second component, the connection system including at least one structural fuse, the at least one structural fuse including:

at least one plate;

at least one first cutout located in a first portion of the at least one plate, the at least one first cutout partially defining at least one first yield region, the at least one first yield region configured to yield upon application of a first load to the plate;

at least one second cutout located in a second portion of the at least one plate, the at least one second cutout partially defining at least one second yield region, the at least one second yield region configured to yield upon application of a second load to the plate, wherein at least a portion of the at least one first yield region is distinct from at least a portion of the at least one second yield region;

wherein the first load is different from the second load; wherein the first component is a beam and the second component is a beam or a wall plate.

15. The frame of claim 14, wherein the second component is a wall plate.

16. The frame of claim 14, wherein the second component is a beam.

17. The frame of claim 16, wherein the at least one structural fuse is attached to a bottom flange of the beam of the first component and a bottom flange of the beam of the second component.

18. The frame of claim 14, further comprising at least one column.

19. The frame of claim 18, wherein:

the at least one column includes a first column and a second column;

the beam of the first component is attached to the first column;

the second component includes a beam that is attached to the second column;

the at least one structural fuse attaches the beam of the first component to the beam of the second component.

20. The frame of claim 18, further comprising a lateral frame attached to the beam of the first component.

* * * * *
